UNITED STATES PATENT OFFICE

116,869

DESIGN FOR A COMBINED POCKET COMB AND CLIP

Guy W. Thompson, Pueblo, Colo.

Application March 30, 1939, Serial No. 83,927

Term of patent 7 years

To all whom it may concern:

Be it known that I, Guy W. Thompson, a citizen of the United States, residing at Pueblo, in the county of Pueblo and State of Colorado, have invented a new, original, and ornamental Design for a Combined Pocket Comb and Clip, of which the following is a specification, reference being had to the accompanying drawing, forming part thereof.

The opposite side from that shown is substantially similar except for the absence of the pocket clip.

I claim:

The ornamental design for a combined pocket comb and clip, as shown and described.

GUY W. THOMPSON.
